HOOD CATCH

Raymond G. Moore, Bridgeport, Conn., assignor
to The Bassick Company, Bridgeport, Conn., a
corporation of Connecticut

Application April 2, 1932. Serial No. 602,775

15 Claims. (Cl. 292—47)

The present invention relates to improvements in hood catches, particularly of the type having catch means interiorly and at each end of the hood, and which are adapted to be operated by a single exteriorly arranged operating handle disposed substantially centrally of the hood. In certain hood catches of this general type, heretofore in use, a rock-shaft or holding rod was employed which was given a torsional tension in the engaged position of the catch to produce the pressure to draw the hood tightly closed, and in order to enable these catches to be manually operated the rock-shaft had to be sufficiently light and flexible as to permit it to be tensioned without an undue expenditure of effort. Also any slight variation in the mounting of the brackets or in the rock-shaft itself, would result in very great differences in the pressure applied, with the result that the hood was apt to be too tightly held at one end while it was loose at the other, or in some cases it would be either too tight or too loose at both ends. Obviously such a structure is subject to vibration, rapid deterioration, and uncertainty 25 and variation in its functioning.

It is an object of the present invention to provide a hood catch in which relatively rigid catch means is employed, so that such means may be made of any desired strength and thickness, and in which relatively uniform pressures will be maintained at both ends of the hood, and such pressures will be approximately maintained at the necessary poundage irrespective of variations in the mounting of the parts. It is particularly proposed in the illustrated exemplary embodiments of the invention to provide spring means associated with the actuating means, and which is under a predetermined pressure in the inoperative position of the catch, this pressure 35 being released as the catch is brought into operative position.

In the above and other objects in view, embodiments of the invention are shown in the accompanying drawings and these embodiments will be hereinafter more fully described with reference thereto, and the invention will be finally pointed out in the claims.

In the drawings:

Fig. 1 is a horizontal sectional view through the hood and frame and showing the catch in plan, the same being in its operative position, and intermediate portions of the hood and rock-shafts being broken away.

Fig. 2 is an interior elevation, also in opera-

tive position, and showing the inoperative position in dotted lines.

Fig. 3 is a vertical sectional view, taken along the line 3—3 of Fig. 2.

Fig. 4 is a vertical sectional view, taken along the line 4—4 of Fig. 2. 60

Fig. 5 is a horizontal sectional view through the hood and frame showing a modified form of catch in plan, the same being in its operative position and intermediate portions of the hood and rock shafts being broken away. 65

Fig. 6 is an interior elevation, also in operative position, and showing the inoperative position in dotted lines.

Fig. 7 is a vertical sectional view taken along the line 7—7 of Fig. 6. 70

Fig. 8 is a detail perspective view of the mounting bracket employed.

Fig. 9 is a horizontal sectional view through the hood and frame, showing another modified 75 form of catch in plan, the same being in its operative position and intermediate portions of the hood and rock-shaft being broken away.

Fig. 10 is an interior elevation, also in operative position, and showing the inoperative position in dotted lines. 80

Fig. 11 is a vertical sectional view, taken along the line 11—11 of Fig. 10.

Fig. 12 is a vertical sectional view, showing a still further modified form of catch. 85

Similar reference characters indicate corresponding parts throughout the several figures of the drawings.

Referring to the drawings, and more particularly to Figs. 1 to 4 thereof, in which I have shown one exemplary embodiment of my invention, the automobile hood 10 is adapted to close in the usual manner against the lacings 11 and 12 of the radiator frame 13 and cowl portion 14 of the chassis. 90

Upon the inner face of the hood, and preferably at a central point between the hood ends, there is riveted or otherwise suitably secured a bracket plate 15 having an outwardly flanged bearing aperture 16 in axial alignment with and having its flange engaged in a slightly larger aperture 17 in the hood. 95

The handle 18 is provided with a reduced diameter shank portion 19, which is engaged in said aperture 16 with a rotary and slightly loose fit, and has a reduced and threaded extension 20 at its inner end. Flats 21—21 are provided upon the shank adjacent the threaded extension 20, and a crank arm 22 is engaged upon this flattened portion of the shank, being provided 100

105

110

115

with a non-circular opening 23 adapted to fit snugly thereon, and being secured by a nut 24. The slightly loose fit of the handle shank in its bearing permits a slight tilting of the crank 5 arm for the purpose of detenting in the operative position, as will hereinafter more fully appear.

The crank arm is bent outwardly from the bracket plate to provide an offset operating end 10 which is domed up and has an aperture 25 therein, in which is swivelly engaged the headed stud 26 of a movement translating bracket member 27, hereinafter more fully referred to. It should be here pointed out that in the operative 15 position the spring means exerts a downward pressure on the bracket member, drawing the crank arm into a tilted position, with the offset end pulled away from the bracket and the other end pressed tightly against the bracket plate, and this action is utilized to detent the 20 crank arm, and thus hold the parts in operative position, as will presently more fully appear.

The bracket plate 15 is provided with a pair of pressed out stop bosses 28 and 29, against 25 which the end of the crank arm 22 abuts in its respective operative and inoperative positions, being arranged so that the operating handle is limited to a definite swing of 90°, the upper limit of this swing being such that the arm is 30 in a central vertical or dead center position, and the lower limit being in a horizontal line at right angles thereto. An arcuate rib 30 is pressed up from the plate, extending from a point contiguous to the boss 29 to a point spaced 35 from the boss 28, to provide a detent pocket into which the end of the crank drops in the operative position under the pressure exerted by the downward pull of the bracket member 27.

The end of the rib is slightly beveled, as at 40 31, so that in releasing the crank arm to permit it to swing to inoperative position the end of the crank arm may be forced out of the detent pocket onto the rib surface. In this position the crank arm frictionally engages the rib surface 45 under slight compression, sufficient to retain the latch parts in inoperative position and against looseness and rattling.

A pair of rock-shafts 32 and 33 are provided 50 upon the interior of the hood extending at each side of the bracket plate 15, being journaled near their inner ends in bearing brackets 34 and 35, preferably curled from the bracket plate 15, and journaled near their outer ends in bearing brackets 36 and 37, secured interiorly to the hood. The rock shafts are bent at their inner 55 end extremities to provide offset crank ends 38 and 39, preferably disposed parallel to the rock-shafts, and at their outer extremities are bent outwardly and longitudinally to provide offset 60 crank ends 40 and 41, also disposed parallel to the rock-shafts, the offset of these crank ends 40 and 41 being relatively greater than that of the crank ends 38 and 39 and also being angularly offset with respect to said crank ends 38 65 and 39.

The crank ends 38 and 39 are loosely engaged 70 in the socket ends 42 and 43 of a coupling member 44, to which the movement translating and actuating means is connected, as will presently 75 more fully appear. The crank ends 40 and 41 are adapted to engage angular keeper brackets 40^a and 41^a, suitably mounted on the radiator and cowl, or upon any other convenient part of the chassis, in proximity to the hood ends. 75 These brackets are illustrated as formed of

sheet metal, and their engaging faces, which are 80 preferably disposed at an angle of about 45°, are respectively provided with pressed out rounded ribs 40^b and 41^b providing positive firm engagement, irrespective of variations in the mounting and disposition of the parts.

The bracket member 27 is of generally rectangular shape, its upper and lower ends being 85 in opposed parallel relation to each other and respectively provided with aligned apertures 45—45 and 46—46, in which are slidingly engaged the legs of a U-shaped yoke member 47, the lower end of which is bent toward the hood and pivotally connected to the coupling member by means of a cross-pin 48 secured within a socket 49 in said member, on which the yoke 90 end is disposed. The socket 49 is arranged to permit swinging movement of the yoke member and there is also sufficient clearance between the yoke and the side walls of the socket, 95 as shown in Fig. 4, to permit the coupling member to swing to a limited extent longitudinally. An apertured cross-bar 50 is provided upon the yoke member at a point below its upper end and within the bracket member 27 and is held 100 against upward movement on the yoke by means of horseshoe washers 51—51 engaged in slots 52—52 in the legs of the yoke, and between this cross bar and the lower end of the bracket helical expansion springs 53—53 are provided on 105 the legs of the yoke, and exert an upward pressure thereon.

In the inoperative or disengaged position of the catch the springs are under an initial pre-determined compression exerted against the 110 ends of the bracket member 27, the cross bar 50 abutting the upper end, as shown in dotted lines in Fig. 2, while in the operative position the bracket is lifted, disengaging its upper end from the cross-bar, and releasing the spring 115 pressure to the catch means so that the springs are further compressed and their pressure is exerted as a lifting force on the yoke, which through its connection with the rock shafts applies pressure to the keeper engaging crank ends 120 40 and 41.

The operation is as follows:—

Swinging of the handle 18 from the inoperative 125 position to the operative position rotates the crank arm 22 and through the yoke member and coupling member rotates the rock shafts and 130 brings the crank ends 40 and 41 into engagement with the keeper brackets. In the disclosed embodiment the rock-shafts are rotated 90°, and due to the fact that the crank arm 22 is 135 longer than the inner crank ends 38 and 39 the crank arm 22 is rotated less than 90° to bring the crank ends 40 and 41 into contact with the keeper brackets. Up to this point the bracket 27, yoke member 47 and springs 53—53 move as 140 a solid member. As further movement of the rock-shafts is prevented the remainder of the 90° movement of the crank arm 22 is utilized to raise the bracket 27 upon the yoke against the pressure of the springs. As soon as the upper 145 end of the bracket is disengaged from the cross bar 50 the springs exert lifting pressure on the yoke, and this pressure is applied to the rock-shafts, the crank ends 40 and 41 then engaging the keeper brackets under this spring pressure.

In the event that any irregularity in the hood or in the mounting of the keeper brackets, or in the independently formed rock shafts, causes one of the crank ends to be engaged before the 150

other the loose connections of the rock shafts with the coupling member 44 is such that the pressure of the springs will not begin to be exerted until the other crank end engages its keeper bracket, whereupon the pressure of the springs will be applied equally to the two crank ends irrespective of such irregularity, and the hood will be held with the same pressure at one end as at the other. The coupling member thus functions as an equalizer between the two rock-shafts.

In Figs. 5 to 8 I have illustrated a modification in which cam means is employed for actuating the catch. A bracket plate 60 is riveted or otherwise suitably secured upon the inner face of the hood, and is provided with an outwardly flanged bearing aperture 61, engaged in the hood aperture 17 in a similar manner to the first embodiment, the handle shank 19 of the handle 18 being rotatably journaled therein.

At the side edges of the bracket plate 60 there are provided vertically disposed parallel guide flanges 62—62 between which a vertically movable slide member 63 is mounted on the plate, a centrally disposed vertical slot 64 being provided therein through which the handle shank 19 extends. Opposed parallel flanges 65 and 66 are bent inwardly from the upper and lower edges of the slide, the upper flange having a pair of circular apertures 67—67 therein, and the lower flange 66 having a pair of slots 68—68 therein in alignment with the apertures 67—67, and which are adapted to guide the spring pressed yoke member, presently to be more fully referred to.

The handle shank 19 is provided in a similar manner to the first embodiment with a threaded extension 20 and flats 21—21, and upon this extension a cam member 69 is secured by means of the nut 24, the cam member having a non-circular aperture 70 for non-rotatable engagement with the shank. This cam member is adapted upon being rotated by the handle to impart vertical reciprocating movement to the slide, and for this purpose the slide is provided adjacent its upper flange 65 and centrally with an outwardly bent vertically disposed cam engaging lug 71, which is engaged by an eccentric lifting cam surface 72 of the cam 69. At each end of this surface 72 there are provided projecting abutment portions 73 and 74, which limit the cam to a movement of 90° between the operative and inoperative positions, a detent pocket 75 being provided adjacent the abutment 73 in which the slide is detented in the operative position.

The cam is provided in opposed relation to the lifting cam surface 72 with an eccentric lowering cam surface 76 which moves in a slot 77 in the lower flange 66 of the slide, bearing against the end of the slot as the cam is rotated to inoperative position to lower the slide. In the operative position the end of the slot 77 is slightly spaced from the cam surface 76, as shown in Fig. 6, to permit the detenting movement of the slide. The flange 66 is ribbed, as at 78, so as to stiffen and reinforce it against bending.

The yoke member 79 is of generally U-shape and has its side leg portions slidably engaged in the slots 68—68 and apertures 67—67 of the slide member, the lower end having a contracted extension 80 connected to the coupling member 44 by means of the cross pin 48 in a substantially similar manner to the first embodiment. The

plate 10 is provided at its lower corner with bearings 81 and 82 similar in arrangement to the bearings 34 and 35 of the first embodiment, and in which the inner ends of the rock shafts 32 and 33 are journaled.

An apertured cross-bar 83 is provided upon the yoke member at a point below the upper flange 65 of the slide, and is held against upward movement on the yoke by means of horseshoe washers 84—84 engaged in slots 85—85 in the legs of the yoke, and between this cross-bar and the lower flange 66 of the slide helical expansion springs 86—86 are provided on the legs of the yoke, friction washers 87—87 being interposed between the spring ends and said lower flange 66. In the inoperative position, as shown in dotted lines, the cross-bar 83 abuts the upper flange 65 and the springs are under an initial predetermined tension, in a substantially similar manner to the first embodiment.

The operation is as follows:

Partial swinging of the handle 18 from the inoperative position, shown in dotted lines, toward the operative position, shown in full lines, rotates the cam 69, causing the slide 63, yoke 79, and springs 86—86 to move upwardly as a unit, and through the connection with the coupling member rotates the rock shafts 32 and 33 to bring the crank ends 40 and 41 into engagement with the keeper brackets, in a substantially similar manner to the first embodiment. The elongated slots 68—68, and the loose engagement of the yoke legs in the apertures 67—67 permits the yoke to swing transversely of the slide, so as to accommodate itself to the swinging arc of the crank ends 38 and 39. As the movement of the handle and cam is continued to the operative position the slide is lifted relatively to the yoke and the spring pressure is thereupon applied to the rock-shaft in a substantially similar manner to the first embodiment. The parts are retained in operative position through the detenting of the lug 71 in the pocket 75 under the pressure of the springs. To disengage the catch the handle is turned in the opposite direction, being first turned with sufficient initial force to overcome the detenting pressure, and being then swung to a point where the lug 71 abuts the cam projection 74, the cam surface 76 pressing the slide downwardly during this movement and through its connection with the coupling member 44 and rock shafts 32 and 33 rotating the crank ends 40 and 41 into inoperative position.

In Figs. 9 to 11 I have shown a further modification in which the latching means is in the form of a rigid vertically shiftable bar. The bracket plate 15^a is similar to that of the embodiment shown in Figs. 1 to 4, but is somewhat longer in its vertical dimension, and along one edge there is bent outwardly therefrom a guide flange 90 having a vertical slot 91 therein, while at the other edge a pair of ears 92 and 93 are bent outwardly and have riveted thereto a guide plate 94, similar to the flange 90, and having a vertical slot 95 therein. This plate 94 is separately formed from the bracket plate to facilitate assembly of the latch bar, as will hereinafter more fully appear.

The latch bar 96 is preferably formed of flat stock, and is engaged at its intermediate portion in the slots 91 and 95 being bent outwardly into offset relation between the guide flange 90 and the guide plate 94, as at 97, to position and retain it against longitudinal dis-

placement. The outer ends of the bar are guided in brackets 98 and 99 riveted to the hood, and adjacent these brackets the extremities of the bar are bent to form angularly disposed keeper engaging ends 100 and 101, adapted to engage with angular keeper brackets 102 and 103 secured to the radiator frame and cowl.

Upon the intermediate portion 97 a pocket member 104 is riveted, and within its tapered 10 pocket there is provided a cross-pin 105 engaged by the lower end of the yoke member 47 in a substantially similar manner to the first embodiment. The taper of the pocket is such as to permit swinging of the yoke member, as 15 shown in dotted lines, and at the same time provides a bearing surface to receive downward pressure of the yoke member during movement to inoperative position. The slot 91 of the flange 90 is provided at its upper end with an enlargement 106 through which the angularly disposed keeper engaging end 101 may be passed in assembling the catch. The operation is substantially the same as the first embodiment, partial 20 movement of the operating handle from the inoperative to the operative position drawing the bar 96 upwardly to engage the ends 100 and 101 with the keeper brackets, and the further movement moving the bracket member 27 relatively to the yoke 47 and thereby applying spring pressure to the bar.

In Fig. 12 I have shown still another modification in which the latch bar 96 is adapted to be actuated by a cam actuated slide 63 and yoke 79, similar to the actuating means shown in 35 the embodiment illustrated in Figs. 5 to 8.

According to present approved automotive practice and requirements the tension deemed necessary and desirable to hold a hood securely in place is calculated at between 30 and 45 40 pounds at each corner of the hood. With the previously known type of hood catch employing a torsional rock shaft holding rod having crank ends engaging keeper brackets at the ends of the hood, and actuated by an intermediate operating handle to twist and tension the rod, the rod is usually made from $\frac{1}{2}$ inch diameter spring wire, and on a hood measuring about 32 or 33 inches, and where the rod has an overall length of about 30 inches, this size wire will exert 45 approximately 30 pounds pressure on each bracket when the parts are all properly placed and in perfect adjustment. This pressure is usually obtained by about a 20 degree twist of the rod, and where the keeper engaging cranks 50 are of $1\frac{1}{8}$ inch length, this measurement being the specified standard at present, this 20 degree twist is equal to a $\frac{1}{16}$ inch action at the end of the crank. Assuming that this $\frac{1}{16}$ inch deflection gives the desired 30 pounds pressure, 55 then for every $\frac{1}{16}$ inch deflection a pressure of $4\frac{1}{2}$ pounds is exerted, and therefore, for every $\frac{1}{16}$ inch variation between the crank and bracket there is approximately $4\frac{1}{2}$ pounds variation in pressure, with a proportionate increase in 60 the manual effort required to operate the catch. Also the pressure varies according to the length of the holding rod, and in cases where the operating handle is not centralized so that a longer portion of the rod is at one side than at the other, an uneven pressure is exerted at each 65 end of the hood.

In the present invention the springs are assembled under a heavy initial pressure, substantially equal to that required to hold the hood. 70 While the following figures are merely given as

an example and are in no way restrictive of the invention, they will serve for comparison with the above figures. Assuming that with the leverages that are used to operate the catch it requires two springs of 60 pounds each at the intermediate part of the catch to give 30 pounds pressure at each end. With a leverage of approximately two to one the springs have a working travel of $\frac{1}{2}$ inch. The initial tension on the springs will be about 50 pounds each, so it is seen that as soon as the keeper engaging crank ends engage the keepers and the movement of the actuating handle is continued to move the springs away from the restraining end of the bracket (27 in Figs. 1 to 4, 65 in Figs. 5 to 8) a pressure of approximately 25 pounds is exerted to press each crank end into engagement with its keeper bracket. This leaves 5 pounds to be distributed over a $\frac{1}{16}$ inch travel to give the total of 30 pounds. Therefore for every $\frac{1}{16}$ inch travel there is only a $\frac{5}{7}$ pound variation, as compared to the $4\frac{1}{2}$ pounds variation with the type of catch above referred to. This means that a variation in the height of a bracket plus or minus as much as $\frac{1}{8}$ inch would be hardly noticeable in the effort required to operate the catch or in the pressure applied at the hood ends.

It will be obvious that the tension may be readily changed simply by employing different 105 strength springs, and this can be done quickly and without any change in the construction or arrangement of the catch. Also it will be understood that the invention is not limited to the use of two springs, but one spring or any desired 110 number may be employed.

I have illustrated and described a preferred and satisfactory embodiment of the invention but it will be obvious that changes may be made therein, within the spirit and scope thereof, as 115 defined in the appended claims.

Having thus described my invention, what I claim and desire to secure by Letters Patent is:—

1. A hood catch actuator for operating keeper engaging catch means, comprising manually operable actuating means for moving said catch means into engagement with the keeper, spring means interposed between the keeper and said actuating means having an initial predetermined tension in the disengaged position of said catch 120 means, and means for receiving the initial pressure of said spring means adapted to be operatively disassociated from said spring means in the engaged position of said catch means with the keeper, whereby pressure of said spring 125 means is applied to press said catch means against the keeper.

2. A hood catch actuator for operating keeper engaging catch means, comprising manually operable actuating means for moving said catch 135 means into engagement with the keeper, spring means interposed between the keeper and said actuating means having an initial predetermined tension in the disengaged position of said catch means, and means for receiving the initial pressure of said spring means adapted to be operatively disassociated from said spring means through abutment of said catch means with the keeper and continued movement of said actuating means against the resistance of said abutment, whereby pressure of said spring means is 140 applied to press said catch means against the keeper.

3. A hood catch actuator for operating keeper engaging catch means, comprising manually op- 150

in said one direction and through engagement of said stop means to be maintained at a predetermined initial tension, said actuating means adapted through said movement translating means to move said catch means into engagement with the keeper and through further movement to move said relatively movable members, relatively to each other to disengage said stop means, whereby pressure of said spring means is applied to press said catch means against the keeper.

13. A hood catch actuator for operating keeper engaging catch means, comprising manually operable actuating means, movement translating means between said actuating means and said catch means comprising a pair of relatively movable members respectively connected to said actuating means and said catch means, stop means adapted to limit their relative movement in one direction, spring means acting between said members normally adapted to press them in said one direction and through engagement of said stop means to be maintained at a predetermined initial tension, said actuating means adapted through said movement translating means to move said catch means into engagement with the keeper and through further movement to move said relatively movable members relatively to each other to disengage said stop means, whereby pressure of said spring means is applied between said catch means and said actuating means, and means for yieldably retaining said catch means in operative position under said spring pressure.

14. A hood catch actuator for operating keeper engaging catch means, comprising manually operable actuating means including a crank, a movement translating link between said actuating means and said catch means comprising a

pair of relatively movable members respectively connected to said actuating means and said catch means, stop means adapted to limit their relative movement in one direction, spring means acting between said members normally adapted to press them in said one direction and through engagement of said stop means to be maintained at a predetermined initial tension, said actuating means adapted through said movement translating link to move said catch means into engagement with the keeper and through further movement to move said relatively movable members relatively to each other to disengage said stop means, whereby pressure of said spring means is applied to press said catch means against the keeper.

15. A hood catch actuator for operating keeper engaging catch means, comprising manually operable actuating means, a movement translating slide between said actuating means and said catch means comprising a pair of relatively movable members respectively connected to said actuating means and said catch means, stop means adapted to limit their relative movement in one direction, spring means acting between said members normally adapted to press them in said one direction and through engagement of said stop means to be maintained at a predetermined initial tension, said actuating means adapted through said movement translating slide to move said catch means into engagement with the keeper and through further movement to move said relatively movable members relatively to each other to disengage said stop means whereby pressure of said spring means is applied to press said catch means against said keeper means.
